UNITED STATES PATENT OFFICE.

JOHN FRANCIS OTIS, OF OSWEGO, NEW YORK.

STEAM-GENERATOR.

1,355,686.

Specification of Letters Patent. Patented Oct. 12, 1920.

Application filed April 11, 1914. Serial No. 831,137.

To all whom it may concern:

Be it known that I, JOHN FRANCIS OTIS, a citizen of the United States, residing at Oswego, in the county of Oswego and State 5 of New York, have invented certain new and useful Improvements in Steam-Generators, of which the following is a specification.

This invention relates to certain improvements in steam generators; and the objects 10 and nature of the invention will be readily understood by those skilled in the art in the light of the following explanation of the accompanying drawings illustrating what I now believe to be the preferred embodiments and mechanical expressions of my invention from among other formations, arrangements and constructions within the spirit and scope of the invention.

An object of the invention is to provide 20 improved means for generating steam particularly where high pressure superheated steam is required and where it is necessary that the generating apparatus be extremely compact to occupy a restricted space both 25 horizontally and vertically.

A further object of the invention is to provide improved means for the generation of superheated steam.

A further object of the invention is to provide 30 certain improvements in steam boiler construction for increasing the durability of such boilers as well as the efficiency thereof.

A further object of the invention is to provide 35 certain improvements in constructions, arrangements and formation of parts whereby an exceedingly efficient and improved steam generating apparatus will be produced.

40 The invention consists in certain novel features in construction and in combinations and arrangements as more fully and particularly set forth hereinafter.

Referring to the accompanying drawings:

45 Figure 1, is a vertical section through steam generating apparatus built in accordance with my invention.

Fig. 2, is a horizontal section on the line 50 2—2, Fig. 1.

Fig. 3, is a horizontal section on the line 3—3, Fig. 1.

Fig. 4, is a section on the line 4—4, Fig. 2.

55 In the particular example illustrated, I show an upright approximately cylindrical boiler having its shell composed of an ap-

proximately flat or horizontal top flue sheet or head 1, an upright inclosing or approximately cylindrical wall composed of upper section 2, and lower section 3, and a crown or 60 bottom flue sheet 4, having a depending annular or cylindrical portion 5, arranged concentrically within and of less diameter than the outer wall section 3, and at its lower end turned outwardly and secured to said outer 65 wall section and in conjunction therewith forming an expansion joint or portion and an annular water leg 6.

A multiplicity of parallel fire flues or 70 tubes 7, extend through the water and steam spaces of the boiler within the outer wall and between the flue sheets and the ends of said tubes are tightly secured and fitted in perforations in said flue sheets as will be understood by those skilled in the art.

The space below the bottom flue sheet and 75 surrounded by the water leg can form a combustion chamber 8, into which the lower ends of the flues open, and if so desired the outer wall of the boiler can be extended downwardly from the water leg to support the boiler and to form the outer wall of a fire brick and cement lined fire box 9, in which any suitable oil or other burner can be arranged. The feed water is usually supplied 80 to the boiler through inlet 12, at the lower end portion of the water leg, although my invention is not so limited.

The outer wall or shell of the boiler is 85 formed with a surrounding or annular inwardly and upwardly curving contraction, inward bulge or depression 10, forming an annular deflecting shoulder or surface 11, overhanging the otherwise open upper end 90 of the water leg 6.

This deflecting shoulder 11, curves inwardly and upwardly over the water leg approximately to a position directly above and spaced from the lower flue sheet 4, so that the annular throat or outlet of the 100 water leg curves and contracts upwardly and hence opens inwardly over said flue sheet to direct the water circulation across the surface of said flue sheet and against the hot lower ends of the flues, and this circulation is aided by the introduction of the feed water into the water leg as hereinbefore described. The purpose of this deflecting shoulder is to prevent direct upward flow of the water from the leg and along the 110 vertical surface of the shell and away from the sheet 4, and lower end portions of the

flues resulting in certain serious disadvantages to the structure as well as in the quality of the steam. I overcome these disadvantages by directing the flow of water inwardly along the top surface of the bottom flue sheet and against the lower portions of the flues where such parts are exposed to the direct heat of the burner and burning gases in the flues thereby protecting said sheet and the flues and maintaining a full supply of water at the points where most needed for the full utilization of the heat in producing superheated steam.

The annular depression 10, is usually formed approximately around the upper end of the casing or shell section 3, so that said bulge terminates in a top horizontal annular out turned flange 13, formed by the top edge portion of said section.

The lower end of the shell section 2, is formed with annular out turned horizontal flange 14, gradually merging into the cylindrical body or portion of the section on a comparatively long inward and upward curve.

The flanges 13, 14, are rigidly secured together to form a tight joint between the sections 3, 2.

The depression 10, is approximately U-shaped in cross section and the flange 13, merges thereinto along curved lines, and hence the sections, 2, 3, are united by an expansion joint permitting longitudinal expansion and contraction of the boiler shell due to approximately flexible or elastic portions formed by the vertical curves thereof particularly by the curved depression 10.

In the particular example illustrated, the top flue sheet 1, is of greater diameter than the interior of the boiler. The upper end of shell section 2, gradually curves upwardly and outwardly to and terminates in a horizontal annular out turned flange 15, arranged under and rigidly fixed to the outer edge portion of said top flue sheet to form a tight joint, also constituting an expansion joint because of the curved portion of the shell joining the flange 15, thereto, as will be readily understood by those skilled in the art.

By thus rendering the vertical shell of the boiler longitudinally elastic or expansible, the shell can yield vertically to accommodate expansion and contraction of the flues, and hence tend to prevent the flues from working loose where fastened in the flue sheets and consequent leakage. By providing the expansion joints in the outer shell, the upper flue sheet can in effect move up and down with the flues as they expand and contract as the outer shell will stretch and contract vertically to permit such movement of the upper flue sheet.

The upper portion of the steam space within the boiler is preferably spanned by a

horizontal separator plate 16, in diameter approximately equal to the internal diameter of the boiler. This separator plate can be supported in any suitable manner as near the flue sheet 1, as practicable, although in the specific example illustrated I show the plate upheld by several inwardly projecting lugs or brackets 17, secured to the boiler shell. This plate is formed with holes individually receiving the flues, and these holes are slightly larger than the flues to provide narrow passages or slits for the upward passage of the steam through the plate. The separator plate is imperforate except for the perforations that more or less closely receive the fire tubes and is designed to prevent passage of water therethrough and also to remove moisture from the steam and to prevent passage of steam except in films along the hot tube surfaces and past the edges of the plate forming the surrounding walls of said perforations. By this arrangement the steam is forced to pass through the plate in films in close contact with the hot walls of the flues for the purpose of superheating the steam and separating water therefrom. The plate becomes highly heated and tends to flash water carried by the steam into vapor, and furthermore, the edges of the plate at the holes therethrough will tend to catch water carried by the steam and separate the same from the steam.

I preferably provide a combustion or hot gas chamber at the top of the upper flue sheet 1, and into which the flues or tubes 7, will discharge the hot or burning products from the combustion chamber 8. For instance, I show an upwardly extending hood 18, mounted on the upper end of the boiler and at the upper end having a suitable outlet or discharge 19. I provide means for passing the steam from the boiler through the combustion chamber within this hood for the purpose of separating all water from the steam and thoroughly superheating the steam before it passes off to perform its work whether for heating or power purposes.

The boiler is provided with a vertical steam outlet pipe or nipple 20, opening into the steam space of the boiler approximately through the center of the flue sheet 1, and this nipple rises from said flue sheet and opens into the center of a combined separator and superheater arranged horizontally within the hood 18, and immediately above the flue sheet 1, and the upper ends of the fire tubes. This superheater is formed with a central top steam outlet or discharge receiving the pipe 21, passing through the hood and exposed to the heat therein and extending to the exterior of the hood. This pipe constitutes the steam offtake or supply through which the steam is supplied for per-

forming the work desired and any suitable means can be provided for controlling the passage of steam therefrom.

The superheater preferably consists of several longitudinally elongated tubular arms or bodies 22, radiating from a common hollow center or hub 23, and the interiors of the hub and arms are spanned by an imperforate baffling plate or diaphragm 24, preferably located centrally or midway between the top and bottom walls of the arms and hub. The interiors of the arms 22 open into the interior of the hub and the arms are otherwise imperforate and the baffling plate spans the hub dividing the interior thereof into a bottom steam inlet space receiving the steam pipe 20 and a top steam outlet space receiving outlet pipe 21. The plate extends from the hub longitudinally within the arms but terminates short of the outer ends of the arms so that each arm has a longitudinal steam passage leading outwardly from the inlet steam space of the hub to a vertical steam port or passage 25, beyond the end of the baffling plate and at the outer end of the arm, and a longitudinal return steam passage above the baffling plate and from port 25, to the upper steam space of the hub.

The steam enters the superheater vertically through pipe 20, and impinges directly against the baffle plate and is then divided into outwardly flowing streams in the several arms and also return flowing streams in said arms, and is thereby subjected to the intense heat under the hood and is thoroughly superheated.

The surfaces and edges of the baffling plate will tend to separate all water from the steam and vaporize and superheat the same.

The superheater is arranged directly above the fire tubes within the zone and influence of the hot burning gases issuing from said tubes and the heat of such combustion is thus fully utilized in superheating the steam sub-divided as it is within and by the superheater.

The superheater with its baffling plate is preferably cast in one piece or otherwise formed integral of suitable metal. The superheater is not claimed herein as it forms the basis of my divisional application for patent filed Jan. 13, 1917, S. No. 142,215.

It is evident that various changes, modifications and variations might be resorted to without departing from the spirit and scope of my invention and hence I do not wish to limit myself to the exact disclosures hereof.

What I claim is:—

1. A vertical fire tube steam generator comprising top and bottom tube sheets, fire tubes carried thereby, and a shell composed of transverse sections having out turned

flanges secured together and merging into their sections on curved lines and forming an expansion joint, one of said sections formed with a curved annular bulge forming a vertical expansible portion, the upper 70 end of said shell being fixed to the top tube sheet and forming an expansion joint, the bottom tube sheet being joined to the lower portion of the shell by means embodying a vertically expansible portion, said bottom 75 tube sheet and the shell forming a water leg, said bulge being arranged over said leg to deflect the water rising therefrom against the lower ends of the tubes, substantially as described. 80

2. A vertical fire tube boiler comprising an outer shell, a top tube sheet secured to said shell, a bottom tube sheet having an annular depending portion in connection with the outer shell forming a water leg 85 provided with the water supply inlet to the boiler, the lower end of said depending portion being turned outwardly and fixed to the shell and forming an expansion joint, and fire tubes secured to said sheets, said 90 shell formed with an expansion joint embodying a curved annular contraction immediately above the water leg forming a deflector to direct the upflow of water from the water leg inwardly across the bottom 95 tube sheet and against the lower ends of the tubes, substantially as described.

3. A vertical fire tube boiler comprising an outer shell composed of sections, the lower end of the upper section having an 100 out turned annular horizontal flange merging along curved lines into the vertical portion of the section, the upper end of the lower section having an annular curved contraction at its upper end curving outwardly 105 and terminating in an out turned annular horizontal flange, said two flanges being fixed together to form a tight joint, upper and lower tube sheets, and fire tubes secured in said sheets, the lower tube sheet coöperating with the shell to form a water leg 110 immediately below said contraction, said contraction forming a deflector to direct the upflowing water inwardly against the lower ends of the fire tubes. 115

4. A vertical fire tube boiler having a depending water leg, the outer shell of said boiler being formed in upper and lower sections at their meeting ends having outturned approximately horizontal flanges rigidly united to form a tight joint, said flanges merging into their respective sections on curved lines to render the shell longitudinally expansible, one of said shell sections being annularly formed with an upwardly 120 and inwardly curving contraction immediately above the water leg to set up a flow of water against the lower ends of the fire tubes. 125

5. A vertical fire tube boiler having a top 130

- flue sheet, an outer shell at its upper end terminating in a flange secured to said sheet, a lower tube sheet having an annular depending portion within the shell and at its lower end fixed thereto and in connection therewith forming a depending water leg, an annular inwardly extending deflector being arranged over the water leg to set up a flow of water across the lower tube sheet,
- 5 10 said shell formed of upper and lower sections having flanges secured together, said flanges merging into the walls of their sections on curved lines, and a multiplicity of fire tubes secured to said sheets and forming 15 the sole connection between the same within the shell.
6. A vertical fire tube steam generator comprising upper and lower tube sheets, a multiplicity of vertical fire tubes secured 20 thereto and forming the sole connection between the sheets within the generator, and a vertical shell to which said sheets are secured, said shell having an intermediate vertically curved annular inward water deflecting 25 bulge extending into the water space of the shell ~~the~~ the lower tube sheet and forming a vertically expansible portion, said shell being vertically expansible with said tubes to prevent loosening of the tubes in 30 the sheets, said generator provided with an annular water leg below said bulge, said water leg provided with the generator water supply inlet, substantially as described.
7. In a steam generator, in combination, 35 an upright inclosing shell comprising an upper section formed with annular expansion joint-forming flanges and curves at its upper and lower ends and a lower section having an expansion joint forming annular 40 curve and horizontal flange at its upper end secured to the lower flange of the upper section, an upper flue sheet secured on the top flange of the upper section, a lower flue sheet formed with a depending annular wall 45 within said lower section and in connection therewith forming an annular water leg, the lower end of said wall being bent to form an annular horizontal flange secured to said lower section and forming an expansion 50 connection, an annular deflector being provided over the water leg to direct flow of water across the lower flue sheet, and a multiplicity of closely-arranged vertical fire tubes extending between and secured in said 55 sheets and constituting the sole connections between the same within the shell.
8. A steam generator having an annular depending water leg into which the feed water for the generator is introduced, said 60 generator embodying a vertical shell, an upper tube sheet secured thereto, a lower tube sheet, vertical fire tubes extending between and opening through said sheets, said shell

having an annular inward bulge rendering the shell longitudinally expansible with said 65 fire tubes, the under side of said bulge forming an annular deflector within the water space of the generator arranged to maintain the generator supplying flow of water from the water leg inwardly on the lower tube 70 sheet and against the lower ends of the tubes.

9. A steam generator comprising an inclosing upright shell, upper and lower tube sheets, a multiplicity of vertical fire tubes 75 opening through said sheets and constituting the sole connection between the same within the shell, said generator having an annular depending water leg internally unobstructed and having the water supply for 80 the generator opening thereto, said shell intermediate its length bent to form an annular inward bulge rendering the shell longitudinally expansible, said bulge in the shell also forming an annular water deflector arranged with respect to the water leg and lower tube sheet to require the generator supplying water occupying and rising from the water leg to flow inwardly 85 across said tube sheet to protect the lower 90 ends of the tubes.

10. A vertical fire tube boiler comprising a vertical shell, upper and lower tube sheets connected thereto, and fire tubes opening 95 through said sheets, an annular portion of said shell extending inwardly, upwardly and outwardly and thus forming an inward annular bulge in the shell rendering the same longitudinally expansible with the fire tubes, said bulge extending inwardly over the bottom tube sheet and forming a water deflector to maintain flow of water across the bottom tube sheet, said boiler having its water supply inlet arranged below said water deflector to maintain said flow of water.

11. A vertical fire tube boiler having a depending annular water leg provided with the boiler water supply inlet, a shell inclosing the water space of the boiler and forming the outer wall of said leg, upper and lower tube sheets secured to said shell, and fire tubes opening through said sheets, said shell being longitudinally expansible and contractile with said tubes and having an annular contracting portion curving inwardly over the water leg and lower tube sheet to direct the boiler supplying water rising from said leg inwardly on the top surface of said sheet to cool the lower ends of the tubes.

In testimony whereof I affix my signature in presence of two witnesses.

JOHN FRANCIS OTIS.
